UNITED STATES PATENT OFFICE

1,964,124

DISPLAY FIXTURE

Daniel J. Keller, Fall Brook, Calif.

Application August 24, 1933, Serial No. 686,624

1 Claim. (Cl. 211—142)

The present invention relates to a display fixture to be used in stores and the like and capable of being set up in a show case or the like.

The object of the invention resides in the provision of a fixture of this nature which is simple in its construction, inexpensive to manufacture, adjustable, foldable, thoroughly efficient and reliable in use, and otherwise well adapted to the purpose for which it is designed.

With the above and numerous other objects in view as will appear as the description proceeds, the invention consists in certain novel features of construction, and in the combination and arrangement of parts as will be hereinafter more fully described and claimed.

In the drawings:

Figure 1 is a perspective view of a fixture embodying the features of my invention showing the same ready for use,

Figure 2 is a perspective view of portions of the fixture folded.

Figure 3 is a perspective view of a slightly different modification or embodiment of the fixture.

Figure 4 is a perspective view of the hypotenuse bar.

Referring to the drawings in detail it will be seen that the frame comprises a vertical bar 5 and a horizontal bar 6 to which is fixed a hypotenuse bar 7. The frame bars 5 and 6 when in set up position are, of course, at a right angle to each other. The bar 5 has its lower end enlarged laterally to provide a plate 8. The bottom edge of the plate is formed with a notch 9 in which a hinge 10 is mounted and attached to the bar 6 at an end adapted to extend into this notch when disposed at a right angle to the bar 5. These bars 5 and 6 may be folded in abutted relationship as shown in Figure 2 when the fixture is not in use. The upper or free end of the bar 5 is bifurcated to receive the bar 7 and to be attached thereto by a bolt 11 extending through one of a plurality of openings 12 provided in the bar 7. The outer end of the bar 6 is also bifurcated and the lower end of the bar 7 extends therein and is fixed thereto by means of a bolt 14 passing through another of the openings 12.

Numerals 15 denote shelves or platforms. On each platform 15 is a bar 16 fixed to the under surface thereof and extending beyond the rear edge thereof and bifurcated to straddle the bar 7 and to be attached thereto by means of a bolt 16 extending through one of the openings 12. These shelves may be mounted at different spaced rela-

tion to each other. The modification shown in Figure 3 differs from the one shown in Figure 1 only in that the hypotenuse bar 7 is longer and extends upwardly to a higher elevation. In other words the bar 7 may be of any desired length. 60

It is thought that the construction, operation, utility and advantages of this invention will now be clearly understood by those skilled in this art without a more detailed description thereof.

The present embodiments of the invention have 65 been described in considerable detail merely for the purposes of exemplification since in actual practice they attain the features of advantage enumerated as desirable in the statement of the invention and the above description. 70

It will be apparent that changes in the details of construction, and in the combination and arrangement of parts may be resorted to without departing from the spirit or scope of the invention as hereinafter claimed or sacrificing any 75 of its advantages.

Having thus described my invention, what I claim as new is:

A fixture of the class described comprising a vertically arranged member having a notch in 80 its upper end and its lower end enlarged to form a base, a notch in the lower edge of the base, a hinge having a part fastened to the upper wall of the notch, a bar, to an end part of which the other part of the hinge is connected, said 85 end of the bar passing through the notch when said bar is arranged at right angles to the base, said bar having its outer end notched, an elongated bar fitting in the notches at the upper end of the first mentioned member and the outer end 90 of the last mentioned bar, said elongated bar having a longitudinally extending row of holes therein, bolts passing through the notched upper end of the vertical member and the notched outer end of the bar and through some of the holes in 95 the elongated bar, a plurality of shelves, a member connected to the lower face of each shelf and extending beyond the rear edge thereof, with the extended portions notched to receive a portion of the elongated bar, and bolts passing through 100 the notched extensions and through some of the holes in the elongated bar.
